(57) **CLAIM**

The ornamental design for an electrically powered steam cleaner, as shown and described.

DESCRIPTION

FIG. 1 is a perspective view of an electrically powered steam cleaner showing our new design;

FIG. 2 is a right side view thereof;

FIG. 3 is a left side view thereof;

FIG. 4 is a top plan view thereof;

FIG. 5 is a bottom plan view thereof;

FIG. 6 is a rear view thereof; and,

FIG. 7 is a front view thereof.

The broken line showing of a handheld steamer is included for the purpose of illustrating and forms no part of the claimed design.
